UNITED STATES PATENT OFFICE.

CLARENCE W. WHEELER, OF CHICAGO, ILLINOIS.

AUTOMATIC ELEVATOR SAFETY DEVICE.

1,310,224.

Specification of Letters Patent.

Patented July 15, 1919.

Application filed April 21, 1917. Serial No. 163,627.

To all whom it may concern:

Be it known that I, CLARENCE W. WHEELER, a citizen of the United States, residing at Chicago, in the county of Cook and 5 State of Illinois, have invented certain new and useful Improvements in Automatic Elevator Safety Devices, of which the following is a specification.

My invention relates to safety devices for 10 elevators generally, but particularly to safety devices for elevators with steel guides; and has for its objects the production of an automatic elevator safety that is relatively easy to install and adjust and that, 15 when in operation, will grip the guides with equal force.

I attain these objects by a mechanism illustrated in the accompanying drawings, in which Figure 1 is a plan view from beneath the floor of an elevator cage and that 20 part of the safety device which is mounted thereon; Fig. 2 is an elevation of the same; Fig. 3 is an enlargement of a portion of the transmission sheave and shaft or 25 screw (the former in section), and of an elevation of the device for preventing said shaft or screw from turning under certain conditions; Fig. 4 is a side elevation of said anti-turning device, showing said shaft or 30 screw in cross-section; Fig. 5 is an end or side elevation of the elevator cage, showing part of the transmission cable in diagram; Fig. 6 is a diagrammatic illustration of the 35 arrangement of the governor and tension sheaves and the transmission cable in relation to the transmission sheave and idler on the cage; Fig. 7 is a view in elevation of the governor with part of its frame broken away; and Fig. 8 is a view of the governor 40 from beneath. The same reference characters refer to the same or corresponding parts throughout the various views.

Referring to said figures, A is the floor of an ordinary elevator cage or car; B B 45 are the guides rigidly mounted on opposite walls or sides of the elevator hatchway; b b are the guide shoes sliding on the guides, and pivotally mounted on the cage or car by means of the brackets c c. Supporting the 50 floor of the cage or car is a pair of channel beams C C, which, together with the angle-irons or frames D D, connecting same with the cage standards or uprights d d, and the frame J, constitute the general frame-work 55 of the device. At each end of this frame,

and pivotally mounted in said angle-irons D D, by means of the pivots e e, is a pair of grip-jaws, mandibles or dogs E E, operating on the principle of levers of the first class, their weight or efficiency arms or ends being 60 loosely disposed on either side of the guides B B. Slidably mounted between anti-friction rollers F F at the extremities of the opposite or power arms of said jaws are the channelled wedges G G, adjustably mounted 65 on the outer ends of the links H H, the said rollers being held in close contact with said wedges by means of the bolts and springs I I. Midway between the angle-irons or frames D D, and between the channel beams 70 C C and firmly and rigidly attached thereto, is the auxiliary mounting frame J; and mounted therein, and slidably through a relatively short amplitude in the directions of said jaws E E, is the bearing K, while 75 pivotally mounted therein and on this bearing by means of the pivot h; is the transmission lever L, which, in turn, is pivotally connected at equal distances from said bearing with the inner ends of the links H H by 80 means of the pivots h. The free end of this lever L extends loosely through and beyond one of the channel beams C, and is pivotally and slidably connected by means of the pivots or lugs n n, with the transmission 85 nut N, mounted on and coöperating, by means of threads, with the transmission shaft O.

In order to avoid difficulties of precise adjustment, which might otherwise arise, the 90 transmission shaft O, is pivotally and slidably anchored to the floor of the cage or car by means of the ball-and-socket bearing P; while its opposite end is pivotally and slidably mounted in the hub of the transmission 95 sheave R, which, in turn, is pivotally mounted in the pillow-block M. On the extremity of this end of the transmission shaft O, and within the hollow of said hub, but without touching it, there is rigidly mounted by 100 means of the projecting stop-pins q q, the high-pitched, double-threaded acceleration head Q, the same coöperating with the transmission sheave R, by means of the threads thereon and the inner ends of the nut-bound 105 screws S S, to draw the transmission shaft O, farther into the hub of the transmission sheave R, when the latter is turned thereon in clockwise direction, the threads being right-handed. To keep said transmission 110

shaft O, from turning while the sheave R, is being thus turned thereon, and the shaft O, is being thus drawn farther into said hub, a key T, is partially embedded longitudinally 5 in said shaft O, about midway the length thereof, and a bracket U, with its free end curved so as to partially embrace but not touch the shaft O, is rigidly and firmly attached, in a corresponding position, to the 10 near channel beam C; and mounted in the extremity of this bracket is a hinged, spring-stressed trigger V, so constructed and disposed that its bit will engage said key and prevent the shaft O, from turning while the 15 sheave R, is being turned thereon, and the said shaft is being drawn thereinto the distance between the pins q q; but slip over it when said sheave or shaft or both are turned in the opposite direction.

20 Mounted on a suitable and rigid bracket at the top of the cage or car, and at such an angle as to permit the transmission cable X, to operate freely of the transmission sheave R, is the idler W to participate in reeving 25 the transmission cable X, around the transmission sheave R; while at the bottom of the hatchway, in an approximate vertical line therewith, and slideable vertically in its frame, there is mounted a standard weighted 30 tension sheave Y; and at the top of the hatchway, and also in an approximate vertical line with said idler, there is mounted a governor sheave Z, designed and equipped with a device to jam and hold the transmission 35 cable from further reeving therearound when the car descends too rapidly, as generally shown in diagram in Figs. 5 and 6.

This governor (Figs. 7 and 8) consists of 40 a frame 1, a sheave 2, mounted therein by means of the pivot 3, the latter also pivotally mounting the equalizer 4, and the shackle 5, but independently of said sheave and of each other. On one side of said sheave, and mounted at one end on the pivots 6 6, between the stops 7 and 8, are the pawls 9 9, 45 their free ends being loosely and adjustably connected with the ends of the equalizer 4, by means of the links 10 10, the bits of said pawls being held within the circumference 50 of said sheave by means of the spring 11. At the bottom of said shackle 5, and rigidly incorporated therewith, its upper portion being loosely disposed within the groove of 55 said sheave, but without touching it, is the shoe 12, having its lower surface or sole grooved to correspond generally with the contour of the transmission cable X. At one end of the frame 1, opposite the grooves of 60 said sheave and shoe, and so disposed that the transmission cable X, will run between it and the toe of said shoe, but normally without touching either, is the spring-stressed shock-absorber 13; while at the bottom, and near the middle of the frame, is 65 the cross-piece 14, for the purpose of stop-

ping and holding the shackle and shoe in ready position, and incidentally to give strength to the frame.

It will be observed that, so long as the sheave 2, revolves at a normal rate of speed 70 or slower, the spring 10, being adjusted to such speed, the bits of the pawls 9 9, will remain within the circumference of the sheave; but that, as soon as it revolves faster, the centrifugal force of the rotation of the 75 sheave will throw the bits of the pawls 9 9, outward and against the stops, and one of said pawls will impinge against the posterior edge of the shoe-shackle 5, and force it forward, carrying the toe and sole of the shoe 80 12, against the transmission cable X, and jamming it against the shock-absorber 13, and, together with the latter, firmly holding it.

The ensemble of the device is so adjusted 85 that the sheaves of the tension and governor Y and Z will turn relatively easier than the transmission and idler sheaves R and W; and since this is so, it will be observed that, so long as the cage or car descends at normal speed, the transmission cable X, will reeve only around the sheaves 90 of the tension and governor Y and Z, and that, under these conditions, the idler W, and the transmission sheave R, will remain 95 stationary; but that, if, for any reason, the cage or car should descend at a speed in excess of the maximum normal, thus causing the shoe of the governor to jam and hold the transmission cable, the latter will immediately 100 begin to reeve around the idler W, and the transmission sheave R, and turn them, under the conditions shown, in a clockwise direction. The first and immediate effect of this operation will be to draw the transmission shaft O, into the hub of the transmission sheave R, until the inner stop-pin q, impinges against the inner ends of the 105 nut-bound screws S S, and the key T, passes the bit of the trigger V, and to do it quickly, 110 thus quickly setting the dogs or jaws E E, upon the guides B B, via the shaft O, the nut N, the lever L, the links H H, and the wedges G G, and their connecting pivots and 115 bearings. Thereupon, should the cage or car continue to descend, the transmission shaft or screw O, will begin to turn in the nut N, along with the sheave R, thus drawing said nut, together with the end of the transmission lever L, pivoted thereto, 120 farther toward said sheave R, and drawing the wedges G G, via the above named parts, connections and bearings, farther in between the rollers F, in the ends of the power arms of the jaws E E, thus causing them to 125 clamp the guides B B, with ever increasing force, and until the friction thereof overcomes the force of gravity acting upon the car, and the latter comes to a stop. And as the bearing K, is constructed and mounted 130

so as to slide, through a small amplitude, in the direction of either of said wedges, the force with which said jaws will clamp the guides B B, will be exactly equal.

5 In order to release the car or cage after the break, or other disorder that caused the same to descend at a dangerous speed, has been repaired, a pinion p , provided with a cross handle-bar r , is inserted through an 10 opening in the floor of the car, lined with a floor-plate f , so as to serve as a bearing for the shank s , of said pinion, and is put into gear with the pinion p' , on the hub of the sheave R, and is then turned clockwise, or 15 so as to unscrew the transmission shaft O, and until the device is again in "set" position. This same thing can be done if desired by simply pulling the transmission cable X, so as to turn the sheave R, in an 20 anticlockwise direction, or so as to unscrew the shaft O. In order to prevent the trigger V, from interfering with this process, the end of its bit is inclined at such an angle as to cause it to slip over the key T, when 25 same comes into contact therewith, while the shaft O, is being turned in an anticlockwise direction.

Modifications and variations can, of course, be resorted to and cultivated, such, 30 for example, as a flat spring to impel the trigger V, as shown in Figs. 1 and 2, instead of a coil-spring, as shown in Figs. 3 and 4; but in so far as they shall not depart materially from the scope and spirit 35 of this invention, they are included therein.

Having thus described my invention, what I claim and desire protected by Letters Patent is:

1. In combination with an elevator-car 40 and its guides, a frame on the car, a pair of jaws in the frame adapted to clamp the guides, a pair of wedges adapted to operate the jaws, a lever to operate the wedges, a screw to operate the lever, a nut to connect 45 and coöperate with the lever and screw, a sheave to operate the screw, a cable to operate the sheave, an idler to aid in operating the cable, a tension sheave to aid in operating the cable and keep it taut, and a governor to aid in operating the cable and to 50 jam it and cause it to operate the sheave when the car descends at a speed above normal.

2. In combination with an elevator-car 55 and its guides, a frame on the car, a pair of jaws in the frame, a pair of wedges to operate the jaws, a lever to operate the wedges, a pair of links to connect the wedges with the lever, a screw to operate the lever, a nut to connect and coöperate with the lever and the screw, a sheave to operate the screw, a cable to operate the sheave, an idler to aid in operating the cable, a tension-sheave to aid in operating the cable and keep it taut, and 60 a governor to aid in operating the cable and 65

to jam and cause it to operate the sheave when the car descends at a speed above normal.

3. In combination with an elevator-car and its guides, a frame on the car, a pair of 70 jaws in the frame, a pair of wedges to operate the jaws, a lever to operate the wedges, a pair of links to connect the wedges with the lever, a slidable bearing in the frame to mount the lever at its fulcrum and equalize 75 the tension on the wedges, a screw to operate the lever, a nut to connect and coöperate with the lever and screw, a sheave to operate the screw, a cable to operate the sheave, an idler on the car to aid in operating the 80 cable, a bracket to mount the idler, a tension-sheave at the bottom of the hatchway to aid in operating the cable and keep it taut, and a governor at the top of the hatchway to aid in operating the cable and to jam and cause 85 it to operate the sheave when the car descends at a speed above normal.

4. In combination with an elevator-car and its guides, a frame on the car, a pair of hinged jaws in the frame operating on the 90 principle of levers of the first class and adapted to clamp the guides, a pair of wedges between the extremities of the power arms of the jaws and adapted to spread them and set the jaws upon the guides, a 95 double-acting lever of the first and second class and adapted to operate the wedges, a pair of adjustable links adapted pivotally to connect the lever with the wedges, a slidable bearing in the frame adapted pivotally to 100 mount the lever midway between the points of connection with the wedges and equalize the tension thereon, a screw to operate the lever, a nut to connect and coöperate with the lever and screw, a sheave to operate the 105 screw, a cable in the hatchway to operate the sheave, an idler on the car to aid in reeving the cable around the sheave, a bracket to mount the idler, a tension-sheave at the bottom of the hatchway to aid in operating the 110 cable and keep it taut, and a governor at the top of the hatchway to aid in operating the cable and to jam and cause it to reeve around the sheave when the car descends at a speed above normal.

5. In combination with an elevator-car and its guides, a frame on the car, a pair of hinged jaws pivotally mounted at the ends of the frame and adapted to clamp the guides, a pair of bolts and springs adapted 120 to stress the jaws off the guides when running normally, a pair of wedges between the extremities of the power arms of the jaws and adapted to set the jaws upon the guides, antifriction rollers pivotally mounted 125 at the ends of the power arms of the jaws to coöperate with the wedges, a double-acting lever of the first and second class adapted to operate the wedges, a pair of adjustable links adapted pivotally to connect the 130

lever with the wedges, a slideable bearing in the frame adapted to mount the lever and equalize its tension on the wedges, a screw to operate the lever, a lugged nut to connect and coöperate with the lever and the screw, a sheave to operate the screw, a cable in the hatchway to operate the sheave, an idler on the car to aid in operating the cable, a bracket to mount the idler, a tension-sheave at the bottom of the hatchway to aid in operating the cable and keep it taut, and a governor at the top of the hatchway to aid in operating the cable and to jam and cause it to operate the sheave when the car descends at a speed above normal.

6. In combination with an elevator-car and its hatchway guides, a frame on the car, a pair of jaws in the frame adapted to clamp the guides, a pair of wedges to operate the jaws, a lever in the frame to operate the wedges, a screw to operate the lever, a nut to connect and coöperate with the lever and the screw, a double-threaded head at the end of the screw to accelerate its initial action, a hubbed sheave on the screw to mount and operate it and coöperate with the double-threaded head, a pillow-block to mount the hubbed sheave on the car, a spring-stressed catch opposite the screw to engage and hold it stationary during the acceleration, a bracket to mount the catch, a cable in the hatchway to operate the sheave, an idler on the car to aid in operating the cable, a bracket to mount the idler, a tension-sheave at the bottom of the hatchway to aid in operating the cable and keep it taut, and a governor at the top of the hatchway to aid in operating the cable and to jam and cause it to operate the hubbed sheave when the car descends at a speed above normal.

7. In combination with an elevator-car and its hatchway guides, a frame on the car, a pair of jaws in the frame adapted to clamp the guides, a pair of wedges to operate the jaws, a lever in the frame to operate the wedges, a screw to operate the lever, a nut to connect and coöperate with the lever and the screw, a high-pitched double-threaded head at the end of the screw to accelerate its initial action, a hubbed sheave on the screw to mount and operate it and coöperate with said head, a pillow-block to mount the hubbed sheave on the car, a spring-stressed catch opposite the screw to engage and hold it during the acceleration, a bracket to mount the catch, a cable in the hatchway to operate the sheave, an idler on the car to aid in operating the cable, a bracket to mount the idler, a tension-sheave at the bottom of the hatchway to aid in operating the cable and keep it taut, and a governor at the top of the hatchway to aid in operating the cable and to jam and cause the cable to operate the sheave when the car descends at a speed above normal.

8. In combination with an elevator-car and its hatchway guides, a frame on the car, a pair of hinged and spring-stressed jaws pivotally mounted at the ends of the frame and adapted to engage and clamp the guides, a pair of wedges adjustably mounted between the power arms of the jaws and adapted to set them upon the guides, antifriction rollers at the extremities of the power arms to facilitate the action of the wedges, a double-acting lever in the frame to operate the wedges, a pair of adjustable links adapted pivotally to connect the lever with the wedges, a screw to operate the lever, a nut to connect and coöperate with the lever and screw, a double-threaded head on one end of the screw to accelerate its initial action, a hubbed sheave at the same end of the screw to mount and operate it, a pillow-block to mount the sheave on the car, a pair of nut-bound pins in the walls of the hub to coöperate with the threads of said head, a pinion on the hub to coöperate with a hand-pinion for releasing the screw, a ball-and-socket bearing adapted pivotally and slidably to mount the other end of the screw and obviate precise adjustment, a spring-stressed catch opposite the shank of the screw to engage and keep it from turning during the acceleration, a bracket to mount the catch, a key embedded in the shank to insure the engagement, a cable in the hatchway to operate the sheave, an idler on the car to aid in operating the cable, a bracket to mount the idler, a tension-sheave at the bottom of the hatchway to aid in operating the cable and keep it taut, a governor at the top of the hatchway to aid in operating the cable and to jam and cause it to reeve around the sheave when the car descends at a speed above normal, and an auxiliary key pinion to coöperate with the pinion on the hub to release the device after its operation.

9. In combination with an elevator-car and its hatchway guides, a frame on the car, a pair of hinged and spring-stressed jaws pivotally mounted in the frame and adapted to engage and clamp the guides, a pair of adjustable wedges to operate the jaws, a double-acting lever of the first and second class to operate the wedges, a pair of adjustable links adapted pivotally to connect the wedges with the lever, a slideable bearing in the frame adapted to mount the lever and equalize its tension on the wedges, a screw to operate the lever, a lugged nut to connect and coöperate with the lever and screw, a high-pitched double-threaded head at one end of the screw to accelerate its initial action, a hubbed sheave at the same end of the screw to mount and operate it, a pair of nut-bound pins in the walls of the hub to coöperate with the threads of said head, a pillow-block to mount the hubbed sheave on the car, a pinion on the hub to aid in releasing

ing the screw, a ball-and-socket bearing adapted pivotally and slidably to mount the other end of the screw on the car and obviate precise adjustment, a spring-stressed 5 catch opposite the shank of the screw to engage and keep it from turning during the acceleration, a key embedded in the shank of the screw to insure the engagement, a bracket to mount the catch, a cable in the hatch- 10 way to operate the sheave, an idler on the car to aid in operating the cable, a bracket to mount the idler, a tension-sheave at the bottom of the hatchway to aid in operating the cable and keep it taut, a governor at the

top of the hatchway to aid in operating the 15 cable and to jam and cause it to reeve around the sheave when the car descends at a speed above normal, and an auxiliary hand-pinion to coöperate with the pinion on the hub to release the device after its operation. 20

In witness whereof I have hereunto set my hand at Chicago, in the county of Cook and State of Illinois.

CLARENCE W. WHEELER.
